A.L. Jackson

ATTORNEY

UNITED STATES PATENT OFFICE

EZRA A. FRANTZ, OF FORT WORTH, TEXAS

BALE-TIE BUCKLE

Application filed April 14, 1931. Serial No. 530,085.

My invention relates to bale tie buckles and more particularly to buckles for cotton bale ties; and the object is to provide buckles which clamp the ends of the bands or ties to prevent creeping or slipping and at the same time hold the end of the band or tie in line with the main portion of the band to prevent the formation of spiders which injure the hands of the workmen, and to provide such construction of the ends of the buckles that the bands or ties will prevent the buckles from giving away under strain. One advantage is that the terminals of the buckles project against the compressed cotton and so slipping is further prevented. The improved buckles comply with the State laws against "spiders". Other objects and advantages will be fully explained in the following description and the invention will be more particularly pointed out in the claims.

Reference is had to the accompanying drawings which form a part of this application.

Fig. 1 is an interior elevation of the buckle after it is engaged by the tie or band.

Fig. 2 is a similar view, but shown in perspective.

Fig. 3 is an edge view of the buckle after it is engaged by the tie or band.

Fig. 4 is a front view while it is being applied to the tie or band.

Fig. 5 is a perspective view of the same.

Similar characters of reference are used to indicate the same parts throughout the several views.

The improved buckle consists of a single piece of steel wire or the equivalent, having side bars 1 and 2 and a tie engaging member 3. The bar 3 is generally applied to the tie or band at the bench. The wire for the buckle is bent to approximately quadrangular form having the members above set forth. The fourth side of the quadrangle is made up of the end portions of the wire which are crossed and included between the lapped member 4 of the tie and the body portion 5 of the tie. The end members 6 and 7 are bent approximately parallel to the tie engaging member 3 in the formation of the buckle to form a locking means with the tie and the end por-

tions are bent out of the plane of members 6 and 7 to form braces 8 and 9 and the end portions are further bent to form locks 10 and 11 which project inwardly beyond the plane of the quadrangular form of the buckle for engaging the compressed cotton. The end member 4 of the tie is locked against lateral movement or shifting and so prevented from making a spider. The buckle is securely locked by the construction and arrangement relative to the tie. The buckle is doubly locked against spreading. The side bars engage the tie at the bend of the tie and then by means of the relatively long shanks 8 and 9 which extend across the tie and lock against the opposite sides of the tie, by means of the terminals 10 and 11.

Operation.—Consider Figs. 4 and 5. The free end of the tie goes next to the bale of cotton. Start the loop of the tie on the members 10, 8, and 6. The loop tie will pass under the members 7, 9, and 11. The buckle may be rotated or turned as may be necessary. As soon as the long or body member 5 of the tie passes the terminal 11, swing the part 5 outwardly and then to the right over the parts 11, 9, and 7. The terminals 10 and 11 will then project inwardly on or past the sides of the tie and so lock the member 4 of the tie and consequently lock the member 5 of the tie against creeping or slipping. The members 6—8 and 7—9 are spaced far enough apart so that the loop of the tie may be passed between these two members. When strain comes on the tie, these members 8 and 9 will be clamped together, as shown in Fig. 3.

Various changes in the sizes, proportion, construction, and arrangement may be made without departing from my invention.

What I claim, is,—

1. A bale tie buckle comprising a steel wire bent to approximately quadrangular form having a tie engaging member and side bars projecting therefrom and said bars being extended substantially parallel to said tie engaging member and then at angles away from the buckle and crossed and the terminals bent at right angles to the plane of the buckle for engaging the edges of the tie to prevent lat-

eral shifting of the tie and to exert friction against the bale.

2. A bale tie buckle comprising a steel wire in combination with a bale tie, said wire being bent to approximately quadrangular form having a tie engaging member and side bars projecting therefrom and bent substantially parallel to said tie engaging member within and substantially to the middle point of the tie and then crossed and bent at angles and extended away from the buckle and to the opposite edges of the tie and the terminals of the wire bent at right angles and projected inwardly past the free end of the tie to exert friction against the bale and to prevent lateral shifting of the tie on the bale.

3. A bale tie buckle comprising a steel wire in combination with a bale tie, said wire being bent to approximately quadrangular form having a tie engaging member and side bars at substantially right angles thereto and then projected approximately parallel to said tie engaging member within and substantially to the middle point of said band and then crossed and then extended at angles away from the buckle and to the lateral edges of the tie and then projected inwardly at approximately right angles to the free end of the tie to form locking means to prevent lateral shifting of the tie, and for exerting friction against the bale.

In testimony whereof, I set my hand this 10th day of April, 1931.

EZRA A. FRANTZ.
